UNITED STATES PATENT OFFICE.

CHARLES W. REINOEHL AND BENT L. WEAVER, OF STEELTON, PENNSYLVANIA.

RAILROAD STRUCTURE.

No. 921,887.

Specification of Letters Patent.

Patented May 18, 1909.

Application filed April 17, 1908. Serial No. 427,688.

To all whom it may concern:

Be it known that we, CHARLES W. REINOEHL and BENT L. WEAVER, citizens of the United States, and residents of Steelton, 5 Dauphin county, State of Pennsylvania, have invented certain new and useful Improvements in Railroad Structures, of which the following is a full, clear, and exact description, reference being had to the accompanying drawings.

The object of this invention is to provide, in a railroad structure, a simple, durable, and efficient means whereby rail sections may be firmly secured together, and to other parts, 15 without liability of the various parts of the structure working loose.

To this end the invention consists in the several novel features of construction and combinations of parts hereinafter fully described and claimed.

In the drawings:—Figure 1 is a plan view of a portion of a railroad frog or crossing embodying our invention. Fig. 2 is a side elevation thereof. Fig. 3 is a transverse section as on the line 3—3, of Fig. 1. Fig. 4 is a plan view of one of the securing bolts.

In the drawings, we have shown our invention applied to a railroad frog or crossing, wherein rail sections are secured together and to other parts. In this construction, 1 and 2 are the stock rails, and 4, the point of the frog. The stock rails are of usual construction, each comprising a head 5, a base 6, and a vertical web 7 extending between the head and base. Usually in frogs of this character, the stock rails 1 and 2 first converge toward the point 4 of the frog and then diverge forming the wing portions, 4^a, which extend laterally of the frog point, as shown 40 in the drawings; and in this type of crossing a hard metal piece 8 is usually inserted between the stock rails, which piece 8 extends into engagement with the head portions 5 and web portions 7 of the rails 1 and 2, a groove or passageway being formed in the 45 piece 8 for the car wheel flanges.

Extending from the webs 7 and the hard metal insert piece 8 are bolts 9. One end of each bolt 9 is screw-threaded for the reception of a nut 10, and the other end of each bolt 9 is provided with an integral head 11, which is arranged between the head 5 and base 6 of the adjacent rail section. The dimensions of the head 11 transversely of the bolt 9 are sufficient to cause the bolt head to

engage either the rail head 5 or base 6, or both, and prevent the turning of the bolt 9.

In the present embodiment of our invention, the head 11 is elongated vertically, so that the top of the head 11 will engage the 60 rail head 5, and the bottom of the head 11 will engage the rail base 6, and thus prevent the turning of the bolt.

When the rail section is arranged at an angle other than a right angle with relation 65 to the securing bolt, we make the inner face of the bolt head 11 at an angle with respect to the bolt to correspond with the angle of the rail section, to secure the proper engagement of the bolt head 11 with the web 7 of the rail 70 section. This feature, together with the feature which prevents the turning of the bolt, obviates the necessity for the employment of a washer between the head of the bolt and the rail section, where the rail section is arranged 75 at an angle other than a right angle with relation to the bolt; for the reason that when the bolt head 11 is permitted to turn between the rail head 5 and rail base 6, it is necessary to employ, between the bolt head 11 80 and the rail web 7, a separate washer having an angular inner face fitting the angle of the rail section and an outer face at right angles to the bolt, against which outer face the bolt head may turn. If no washer be employed, 85 and if the angular face engaging the rail web be formed on the bolt head, and the head is permitted to turn, the bolt head would be liable to turn and move its face out of proper engagement with the rail web, and thus defeat its object.

In each instance where the bolts 9 extend through the rails 1 and 2 at points where the rails 1 and 2 converge or diverge with relation to each other and are not parallel to 95 each other, or substantially so, we insert between the nut 10 and the adjacent rail web 7 a washer 12 having an inner face fitted to the face of the rail web, and an outer face at right angles to the bolt 9; and between the 100 washer 12 and the nut 10 is the usual split washer nut-lock 13. Where the bolts 9 extend through the rails 1 and 2 at points where the rails are parallel to each other, or substantially so, the washers 12 may be dispensed with, in which event only the split washer nut-locks 13 will be present between the nuts 10 and the adjacent rail webs. Thus it will be seen that when the parts are 105 assembled and the nut 10 is tightened to 110

firmly draw and secure the parts together, the bolt head 11 will serve to prevent the turning of the bolt during the tightening of the nut 10 and will also serve to prevent any liability of the parts working loose after the nut 10 has been tightened.

Having thus described our invention, we claim as new and desire to secure by Letters Patent:—

- 10 1. In a railroad structure, the combination of a rail section having a vertical web and laterally extending parts, a part to which said rail section is secured, and a securing bolt extending through the web of said rail section and said part, said bolt having an integral head extending transversely of the bolt sufficiently to cause said head to engage one of said laterally extending rail parts and prevent the turning of the bolt, substantially as described.
- 15 2. In a railroad structure, the combination of a rail section having a vertical web, a head and a base, a part to which said rail section is secured, and a securing bolt extending through the web of said rail section and said part, said bolt having an integral head arranged between the rail head and the rail base, and extending transversely of the bolt sufficiently to cause said bolt head to engage said rail head and said base and prevent the turning of the bolt, substantially as described.
- 20 3. In a railroad structure, the combination of a rail section having a vertical web, a head and a base, a part to which said rail section is secured, a securing bolt extending through the web of said rail section and said part, said bolt having an integral head elongated vertically sufficiently to cause it to engage said rail head and said base and prevent the turning of the bolt, substantially as described.
- 25 4. In a railroad structure, the combination of a rail section having a vertical web and laterally extending parts, a part to which said rail section is secured, and a securing bolt extending through the web of said rail section and said part at an angle

other than a right angle with relation to said rail section, said bolt having an integral head extending transversely of the bolt sufficiently to cause said head to engage one of said laterally extending rail parts and prevent the turning of the bolt, the inner face of said bolt head being at an angle other than a right angle with relation to the bolt and fitting the angle of said rail section, substantially as described.

5. In a railroad structure, the combination of a rail section having a vertical web, a head and a base, a part to which said rail section is secured, and a securing bolt extending through the web of said rail section and said part, at an angle other than a right angle with relation to said rail section, said bolt having an integral head arranged between the rail head and the rail base and extending transversely of the bolt sufficiently to cause said bolt head to engage said rail head and said base and prevent the turning of the bolt, the inner face of said bolt head being at an angle other than a right angle with relation to the bolt and fitting the angle of said rail section, substantially as described.

6. In a railroad structure, the combination of a rail section having a vertical web, a head and a base, a part to which said rail section is secured, a securing bolt extending through the web of said rail section and said part at an angle other than a right angle with relation to said rail section, said bolt having an integral head elongated vertically sufficiently to cause it to engage said rail head and said base and prevent the turning of the bolt, the inner face of said bolt head being at an angle other than a right angle with relation to the bolt and fitting the angle of said rail section, substantially as described.

In testimony whereof, we have hereunto affixed our signatures.

CHARLES W. REINOEHL.
BENT L. WEAVER.
